(No Model.)

J. CLAPP.
AUTOMATIC VALVE.

No. 425,752.

Patented Apr. 15, 1890.

UNITED STATES PATENT OFFICE.

JOSEPH CLAPP, OF EVANSTON, ASSIGNOR TO THE CLAPP AUTOMATIC FIRE EXTINGUISHER COMPANY, OF CHICAGO, ILLINOIS.

AUTOMATIC VALVE.

SPECIFICATION forming part of Letters Patent No. 425,752, dated April 15, 1890.

Application filed July 29, 1889. Serial No. 319,022. (No model.)

To all whom it may concern:

Be it known that I, JOSEPH CLAPP, of Evans-
ton, in the county of Cook and State of Illi-
nois, have invented certain new and useful
5 Improvements in Automatic Valves, of which
the following is a full, clear, and exact de-
scription, reference being had to the accom-
panying drawings, forming a part of this
specification, in which—

10 Figure 1 is a vertical sectional view of my
improved valve as it appears when closed, to-
gether with a portion of a "dry-pipe" system
with which it is connected; and Fig. 2 is a like
view of said valve when open.

15 Like letters of reference in both figures in-
dicate like parts.

My invention has reference more particu-
larly to valves adapted to control the flow of
water from the supply to the distributing
20 pipes of an automatic fire-extinguishing ap-
paratus, and is especially applicable to what
is commonly known as the "dry-pipe system,"
my object being to provide a diaphragm-valve
in operative connection with the main valve,
25 and having a secondary or supplemental valve
forming a part thereof, which is arranged to
move in the same directions, respectively, with
the main valve when opening or closing.

To these ends my invention consists in the
30 combination of the elements hereinafter more
particularly described and claimed.

Referring to the drawings, A A' represent
the two parts of a metal case or shell within
which the valves are inclosed, as hereinafter
35 stated. Said parts are provided with the usual
flanges a a', which are bolted together, as
shown, and between which is interposed a flexi-
ble diaphragm B, of any suitable material—
such as rubber or sheet metal—but prefera-
40 bly of corrugated sheet-brass, the corrugations
being circular and concentric with the axis
of its shell. An opening is formed in the cen-
ter of the diaphragm, around which is placed
rings b b', which are rigidly attached to said
45 diaphragm in any well-known way. Upon the
ring b is formed a valve-seat b². A rigid de-
pending frame b³ is formed upon or attached
to the ring b', to the bottom of which and in the
line of the axis of the shell is attached, pref-
50 erably by means of a ball-and-socket joint, as

shown, a valve C in operative proximity to a
valve-seat a², formed upon the lower section
a' of the case. A neck a³, having a screw-
thread formed thereon, serves as a means for
attaching the service-pipe D. Into the neck 55
a⁴ of the part A is screwed an annular nut E,
having inner and outer screw-threads formed
thereon, and to which is attached the main
distributing-pipe F. A cross-bar e is attached
to the interior of the nut E, and a like cross- 60
bar b⁴ is attached to the ring b', both of said
cross-bars being bored to receive a valve-stem
g, which is loosely inserted therein, and to
which is attached a valve G, adapted to rest
normally by its own gravity upon the valve- 65
seat b². An opening h is formed in the part
A' of the shell to permit the escape of water
in case the valve C should leak.

With the main distributing-pipe is con-
nected the usual branch distributing-pipes, 70
one of which is shown at f, having automatic
sprinklers f', the valves of which are normally
held in position by means of fusible solder.
With the pipe F is also connected an air-pipe
H, in communication with an air-pump J, and 75
provided with a pressure-indicator J' and a
check-valve j'.

The operation of my improved valve is as
follows: Assuming the water-pressure to be
temporarily shut off from the service-pipe D 80
and the valves of the automatic sprinklers f'
closed, the air is compressed in the distribut-
ing-pipes by means of the pump J until a
sufficient pressure is indicated upon the gage.
The valve G becomes seated by its own grav- 85
ity, and that, with the diaphragm B, is acted
upon by the air-pressure in the chamber A²
and closes the valve C. Water is then ad-
mitted to the service-pipe D; but the pressure
of the diaphragm thereon is sufficient to re- 90
tain the valve C firmly closed. Upon the
opening of a sprinkler f', and the consequent
escape of the air from the distributing-pipes,
the valve C is opened by the pressure of wa- 95
ter from beneath. The water enters the cham-
ber A³, lifts the valve G, enters the chamber A²,
and thence passes freely to the distributing-
pipes. It is obvious that as soon as the water
is shut off and the pipes drained the opera-
tion may be repeated. 100

Having thus described my invention, I claim—

1. A differential valve consisting of a closed shell, a flexible diaphragm having a central opening, a valve for closing the service-pipe, means—such as a frame—for connecting the same with said diaphragm, a valve-seat upon the opposite side of said diaphragm, and a loose valve arranged in operative connection therewith, substantially as shown and described.

2. In a differential valve, the combination of a hollow shell, induction and eduction openings, a diaphragm arranged within said shell, a central opening therein surrounded by a valve-seat upon the side facing the eduction-opening, a loose valve in operative connection with said valve-seat, a valve-seat surrounding the induction-opening, and a valve attached to said diaphragm for normally closing said induction-opening, substantially as shown and described.

3. The combination, with the supply and distributing pipes of a fire-extinguishing system, of a differential valve having induction and eduction openings connected with said pipes, respectively, a diaphragm arranged within said shell, a central opening therein, a valve-seat thereon surrounding said opening upon the side facing the eduction-opening, a loose valve in operative connection with said valve-seat, a valve-seat surrounding the induction-opening, and a valve attached to said diaphragm for normally opening said induc-

tion-opening, substantially as shown and described.

4. In a diaphragm-valve, the combination of a shell having induction and eduction openings, of a diaphragm having a central opening and valves arranged upon opposite sides thereof, one attached to said diaphragm for closing said induction-opening and the other adjusted loosely for normally closing the opening in said diaphragm, substantially as shown and described.

5. The combination of the shell A A', diaphragm B, having a central opening, valve-seat a^2 , valve C, attached to said diaphragm, valve-seat b^2 , and valve G, loosely arranged in operative proximity to said seat, substantially as shown and described.

6. The combination, in a diaphragm-valve, of a diaphragm, a valve loosely arranged upon one side to close an opening therein, and a valve upon the opposite side and attached to said diaphragm for closing the induction-opening, said valves being arranged to move in the same direction when opening and closing, respectively, substantially as shown and described.

In testimony whereof I have signed this specification, in the presence of two subscribing witnesses, this 18th day of July, 1889.

JOSEPH CLAPP.
